UNITED STATES PATENT OFFICE.

ERVIN M. FITZ, OF COLUMBUS, OHIO.

ELECTRIC SWITCHING MECHANISM.

1,182,080.

Specification of Letters Patent. Patented May 9, 1916.

Application filed March 5, 1913. Serial No. 751,996.

To all whom it may concern:

Be it known that I, ERVIN M. FITZ, a citizen of the United States, residing at Columbus, in the county of Franklin and State of Ohio, have invented certain Improvements in Electric Switching Mechanism, of which the following is a specification.

My invention is an electric switching mechanism comprising, in its preferred form, journaled devices having contacts and containing a fluid adapted for electrically connecting and disconnecting said contacts in different positions of said devices, in combination with solenoids having contacts operating with contacts aforesaid to control various circuits and plunger mechanism by which said devices are oscillated to vary the relations of said contacts, the solenoid circuits being controlled by electrically operated means adapted for opening and closing them in alternation and thereby effecting the oscillation of said devices.

A particular application of my improvements is found in lighting systems involving the use of a storage battery connected with a generator adapted to be operated by the axle of a car.

It is a leading object of my invention to improve lighting and other systems in which a generator and storage battery are used in conjunction, by providing efficient means for opening the field circuits of the generator when running above a certain critical speed and when the battery connected with said generator has been charged to the desired degree, as also to close the field circuits when the battery has reached a predetermined discharge point. A desideratum effected is the prevention of arcing between slowly separating contacts used in the system by automatically breaking the circuits through said contacts prior to their separation.

The characteristic features and advantages of my improvements will more fully appear by reference to the following description and the accompanying drawings in illustration thereof.

In the drawings, Figure 1 is a top plan view of a switch embodying improvements of my invention; Fig. 2 is a longitudinal sectional view of the same taken transversely through the oscillating barrels; Fig. 3 is a transverse sectional view of the mechanism taken through the axes of the barrels; Fig. 4 is a sectional view taken through the

longitudinal axes of the solenoids transversely to the oscillating barrels; and Fig. 5 is a diagrammatic representation of my improvements applied to train lighting. 60

The apparatus, as illustrated in the drawings, comprises a double solenoid mercury switch having the cover 1 fixed to the base 2 to which is fixed the solenoid coils 3 and 3^a adapted for reciprocating a plunger consisting of the ends 4 and 4^a (movable in the respective coils) and the intermediate circular rack 4^b, the plunger having a hand 4^c fixed thereto and movable in the slot 1^a of the cover. Bearings 5 and 5^a, fixed to the 70 base 2 by bolts 6 and 6^a and holding the respective coils 3 and 3^a, support the respective contact brushes 7 and 7^a, 8 and 8^a, 9 and 9^a and 10 and 10^a. Barrels 11 and 12 are journaled on the respective arbors 13 and 14 75 which are fixed to the base 2, the barrels having the respective racks 11^a and 12^a engaging the rack 4^b. The barrel 11 is provided with the circular contacts 11^b which engage the respective brushes 7 and 7^a and have the studs 11^c extending into the barrel's chamber 11^d which contains the mercury 11^e; the barrel is also provided with the circular contacts 11^f which engage the respective brushes 9 and 9^a and have the studs 11^g which extend into the mercury chamber 11^d. The barrel 12 is provided with the circular contacts 12^b which engage the respective brushes 8 and 8^a and have the studs 12^c which extend into the barrel's chamber 12^d containing the mercury 12^e; this barrel is also provided with the circular contacts 12^f which engage the respective brushes 10 and 10^a and are connected with the studs 12^g which extend into the barrel's chamber 12^d containing the mercury 12^e. It will be understood that the bodies of the barrels containing the contacts, studs, chambers and mercury are made of insulating material, or so that the necessary insulation is effected. 90 The ampere hour meter 13 has the contact points 13^a and 13^b connected by the respective conductors 14 and 15 with the respective brushes 7^a and 9^a and therethrough with the corresponding contacts 11^b and 12^b. These contacts are connected by the conductors 11^c alternately with the respective complementary contacts 11^f and 12^f engaging the respective brushes 7^a and 9^a. These brushes are connected by the conductors 7^a and 9^a with the respective coils 3 and 3^a which are connected by the conductors 16 and 16^a with 100 105 110 115 120 125 130 135 140 145 150

the conductor 22. The meter has a movable hand 13^c adapted for making contact with the respective points 13^a and 13^b and connecting them with the conductor 13^c of the meter. The conductor 13^c is connected by a conductor 17 with the battery 18 and by a conductor 19^c with the solenoid coil 19^a, which is connected by the conductor 19 with the generator 20, and the battery and generator are connected by the conductor 24. The fields of the generator are connected by the conductors 25 and 26 with the contacts 8 and 8^a and by the conductors 27 and 28 with the contacts 10 and 10^a.

15 The conductor 19 is adapted to be connected with the lamp or work circuit conductor 21 through the solenoid coil 19^a, the resistance 33 and the contacts 30 and 32 when connected by the conductor 29 on the 20 solenoid plunger 19^b, which takes place when the generator is working and sufficient current passes through the coil 19^a to move the plunger 19^b and conductor 29 to the position shown in Fig. 5. When, by reason of a reduction in the current, the plunger 19^b causes the conductor 29 to connect contacts 30 and 31, the conductor 21 is directly connected with the conductor 17 by the conductor 34, the resistance 33 being cut 25 out of circuit. The conductor 21 is connected with the conductor 22 through the lamps 23, and the conductor 22 is connected by the conductors 16 and 16^a in circuit with the coils 3 and 3^a and the conductor 24 connecting the battery 18 and generator 20. When the generator 20 is working and charging the battery 18, current flows from the generator 20 through the conductors 19, 19^a, 19^c, 13 and 17 to battery 18 and thence 30 through conductor 24, and through the field circuits comprising the conductors 25 and 26 (connected by their terminal brushes 8 and 8^a, through the contacts 12^b, studs 12^c, and mercury 12^d) and the conductors 27 and 28 (connected by their terminal brushes 10 and 10^a through the contacts 12^f, studs 12^g and mercury 12^h), the mechanism being in the position shown in Figs. 4 and 5. As soon as the hand 13^c is carried to the point 35 13^a, by current passing through the meter 13 in the circuit containing the conductors 19^c and 17, a shunt circuit is completed, from the conductor 19^c through the conductors 13^c, 13^a, 14, 7^a, 11^b, 11^c, 11^e, 7, 3', 3, 16 and 22 to 24. The solenoid coil 3, being thus excited, draws the plunger end 4 into it and revolves the barrels 11 and 12 to the position shown in Figs. 1 and 2, thus 40 breaking its own circuit to the meter 13 by removing the mercury 11^e from the studs 11^c and opening the field circuits by removing the mercury 12^e from the studs 12^c and the mercury 12^h from the studs 12^g. The mercury 11^e now connects the studs 11^f and, 45 through the corresponding contacts 11^f, the terminal brushes 9 and 9^a, whereby the connections for the solenoid coil 3^a are set, the circuit thereof being completed when the hand 13^c touches the point 13^b. The generator is now idle, the batteries are discharging, and the meter hand 13^c is moving toward the point 13^b, and, when contact is made therewith, a shunt circuit is completed and current flows from the conductor 17 through the conductors 13^c, 13^a, 13^b, 15, 9^a, 75 11^f, 11^g, 11^e, 11^f, 9, 3'', 3^a, 16^a and 22 to 24. The excited solenoid 3^a now draws the end 4^a of the plunger into it and revolves the barrels 11 and 12 to the position shown in Figs. 4 and 5, thus breaking its 80 own circuit to the meter 13 through the mercury 11^e by removing the latter from the studs 11^g, resetting the circuit through the solenoid 3 by causing the mercury 11^e to connect the studs 11^e, and completing the 85 field circuits by causing the mercury 12^h to connect the studs 12^g and the mercury 12^e to connect the studs 12^f.

By means of the hand 4^c, the plunger connected therewith can be reciprocated manually to operate the mercury switch and control the generator's field circuits, the position of the hand also indicating the status of the apparatus.

It will be understood that current is flowing through the work or lamp circuit, comprising the conductors 21 and 22, whether the generator is working or idle; and that the connection is made from the conductor 19 to the conductor 21 through the coil 19^a 100 and the resistance 33 when the current strength is sufficient to move the solenoid plunger 19^b so as to cause the conductor 29 to connect the conductors 30 and 32, while the resistance 33 is short circuited and the connection is made through the conductors 34 and 17 when the conductor 29 connects the contacts 30 and 31 due to a reduction of current or the opening of field circuits 25—26 and 27—28.

Having described my invention, I claim:

1. In apparatus of the character described, a set of contacts, a journaled device having contacts coacting with said first named contacts, said device having a chamber containing a liquid for connecting its said contacts, a second set of contacts, a journaled device having contacts coacting with said second set of contacts, said second named device having a chamber containing a liquid for connecting its said contacts, and electromagnetic mechanism for simultaneously turning said devices in opposite directions.
2. In apparatus of the character described, a pair of solenoid coils, a plunger disposed in and adapted to be operated by said coils, a rack on said plunger, a plurality of barrels having teeth thereon engaged and adapted to be operated by said 130

rack, and means whereby one of said barrels controls the operation of said plunger, the other of said barrels having means for controlling an electric circuit.

5 3. In apparatus of the character described, journaled mechanism having a plurality of sets of contacts, electromagnetic mechanism adapted for rotating said journaled mechanism, a set of contacts coacting with a set of said first named contacts, a set of contacts coacting with a second set of said first named contacts, a set of contacts coacting with a third set of said first named contacts and connected with said electromagnetic mechanism, a set of contacts coacting with a fourth set of said first named contacts and connected with said electromagnetic mechanism, and means for connecting the respective contacts of each of 20 said sets of contacts carried by said journaled mechanism.

4. In apparatus of the character described, a journaled toothed barrel having peripheral contacts, brushes adapted for engaging said contacts, a conducting liquid carried by said barrel and adapted for connecting said contacts, and a solenoid having a plunger provided with a rack engaging the teeth of said barrel.

20 5. In apparatus of the character described, a pair of independently journaled barrels each having contacts and containing insulating chambers respectively provided

with a conducting liquid, the liquid in the respective chambers adapted for connecting and disconnecting respective sets of said contacts in different positions of said barrels, in combination with electrical mechanism comprising contacts adapted for coacting with respective contacts aforesaid 40 and means for turning said barrels.

6. In apparatus of the character described, a pair of independently journaled barrels each having insulated peripheral contacts concentric with the axis thereof and containing insulated chambers respectively provided with a conducting liquid, the liquid in the respective chambers adapted for electrically connecting and disconnecting respective sets of said contacts in different positions of the respective barrels, in combination with electrical mechanism comprising contacts adapted for coaction with respective contacts aforesaid, electromagnetic mechanism electrically connected with 55 contacts second named, and a plunger adapted to be reciprocated by said electro-magnetic mechanism and to oscillate said barrels.

In testimony whereof I have hereunto set my hand this 20th day of February, 1913, 60 in the presence of the subscribing witnesses.

ERVIN M. FITZ.
